PROTECTOR FOR ICE IN TRANSIT

Application filed July 5, 1929. Serial No. 376,020.

These improvements relate to means for protecting ice being shipped in freight cars and the like. Its chief advantage is in connection with what is known as manufactured 5 or artificial ice.

Ice manufactured for commercial purposes is made in open-top cans of various dimensions, and the rectangular cakes weigh usually from one hundred pounds up to four 10 hundred pounds. Such manufactured ice is peculiarly fragile, and so fragile indeed that for the most part manufacturers refuse to ship such ice by rail.

When ice in such cake form is packed for 15 shipment in a box car the cakes are set on edge and positioned side by side in laterally-extending rows from one side of the car to the other. After one such lateral series has been set down another series just like it is set 20 on top of the first. In this way the floor space is covered with a double thickness of the cakes, that amount making a carload. The cakes are applied at the ends of the car first and the structure is built up toward the 25 middle where finally the cakes are wedged and packed together so as to keep the whole mass as much as possible from moving relative to the car.

Owing to the jolting of the car in transit, 30 especially the shocks due to sudden starting and stopping and the impacts incident to shifting the car in the yards, etc. the car arrives at its destination with the artificial or manufactured ice badly cracked and split 35 apart, and usually to a large extent broken up in substantially small masses. I have received at least one shipment of artificial ice coming not more than fifty miles in which I believe there was not a single cake intact, and the carload as a whole was in such broken up 40 condition that the commercial disposition of it resulted in actual loss.

It may be mentioned that natural ice when 45 packed as described may safely be shipped even long distances without material damage under the ordinary conditions of freight service. Natural ice is peculiarly strong. A cake of it suspended will often ring like 50 a bell when struck with a hammer. It breaks

and chips entirely differently from the manufactured ice.

The very notable differences between the two kinds may, no doubt, be attributed to the different methods of freezing. In the case 55 of natural ice the freezing extends gradually downward from the surface of the water, while in the manufactured ice it extends inward from the sides and upward from the bottom. In the middle portions of the artificial cake there are usually accumulations of foreign matter and apparently well-defined cleavage areas or surfaces. In any event the manufactured cake as a whole is structurally 60 weak.

The present invention is directed to means for rendering commercially feasible and satisfactory the shipping of manufactured ice in the form of cakes and slabs as ordinarily produced, to the end that districts outlying from a given source of manufacture may 65 be supplied with ice at times when the natural crop has failed or becomes exhausted, and whereby the commercial field for artificial or manufactured ice may be enlarged.

I am not aware that any device for this 70 purpose has heretofore been suggested. It has been common to use lumber at various places in the car, to pack the cakes more tightly, but without success so far as the breakage in question is concerned. It is not considered feasible to pack the ice in sawdust as it must 75 be delivered in a clean condition, and cleaning it would be objectionably expensive. Furthermore, it would be expensive and no doubt prohibitive to pack the ice in sawdust 80 at the loading point.

In the drawings Figure 1 is a fragmentary 85 sectional view transversely of a car body showing two transverse tiers or rows of ice arranged in the usual way and with the present invention normally applied and seen in face view;

Fig. 2 is a fragmentary sectional longitudinal view of the car body showing several of the transverse rows of the ice blocks, with the present invention applied between adjacent rows; and

Fig. 3 is an enlarged detail of one of the supports or hook elements with a fragment of 90 100

the shield, guard, or protector element attached thereto.

The shield or protector proper, in its preferred form, comprises a network adapted to overlie an exposed face of a tier of the cakes. It is illustrated as comprising a plurality of transversely-extending buffers or shock absorbing elements 10, 11, 12 and 13, shown in the form of ropes which may be suitably 5 an inch or more in thickness and which may be of good quality or of such coarse rope material as various kinds of grass, other fibre, straw, etc. I prefer to use coarse hemp rope for the purpose, for the sake of durability and 10 cheapness. Preferably two such elements as 15 10 and 11 extend across the exposed ends of the upper transverse tier of blocks marked *a* to *i* inclusive while two other such elements as 12 and 13 extend across the exposed ends 20 of the lower tier, namely blocks marked *j* to *r* inclusive. These buffer or shock-absorbing elements 10 to 13 inclusive are held suspended 25 by smaller ropes 14, 15, 16, 17 and 18. These vertically-extending ropes as 14 are severally passed between strands of the transverse ropes as 10 and a knot 20 in each vertical rope above the transverse ropes respectively and a similar knot 21 below the transverse ropes hold the latter upon the vertical 30 ropes respectively. The network thus formed extends across the ends of the blocks of the two transverse tiers as shown by Fig. 1.

The vertical ropes numbered 14 to 18 inclusive are secured by tying them to the respective supporting members 25, each shown as a piece of iron having the upright part 26 and the normally horizontal part 27, the latter having a point 28 turned normally downward and adapted to catch upon the upper 40 surface of a cake of ice. The part 26 has a hole 26^a at its lower end to accommodate the rope as 14.

Fig. 2 shows how the device spaces apart the blocks of the respective transverse rows 45 or tiers.

The transverse ropes 10, 11, 12 and 13 are fairly stiff so that although the end supports 50 may be placed about midway of a given end cake of ice as *a* and *i* (Fig. 1), the free ends as 10^a, 11^a, 12^a, and 13^a of the transverse ropes project laterally and extend the desired protection substantially from side to side of the tier arrangement.

Two tiers of ice cakes having been built 55 up as in Fig. 1 the protective network is applied by simply hanging it from the upper surface of the upper tier as shown. The sharp points 28 of the supports 25 enter or catch into the ice and hold the device in place. It is a simple operation to position the device 60 as a whole. The next operation is to build up a second tier of blocks against the network, and then another buffer or shock-absorbing device is applied to the face of that 65 tier, and so on.

There is thus provided between the transverse tiers cushioning material adapted to absorb to a large extent the shocks and jars incident to freight travel and importantly, the ice cakes are thus maintained apart at what 70 has heretofore been their abutting ends. When they are end to end and a sudden shock occurs they at once go into fragments.

It would be feasible to have cushioning material, for example such as 10, 11, 12 and 13, 75 extend vertically, as by suspending such material from a plurality of supports or supporting members. By extending them transversely however I believe a more practical and serviceable device is produced than in some 80 other arrangement. I have illustrated rope sections and the network form of device as being probably the most practical and serviceable. The kind and character of the cushioning material may vary, however, within 85 wide limits. The device as a whole should be of substantially low cost, and is preferably strong and durable and readily to be applied and removed and otherwise handled. These 90 desiderata are present in the form illustrated.

Where the device is made of strong and substantial material and construction, as is the one illustrated, it may be used many times, provided the consignee ships it back to the manufacturer of the ice. One advantage of 95 the flexible character of the device as a whole is in its ease and convenience of handling, not only when applying and removing it, but also in shipping it back, for which purpose burlap bags may be used, or several of the devices 100 may simply be tied up with rope into a bundle and tagged. It occupies but little space when in use, and is of such character that when normally applied only a slight movement of the ice body as a whole may take place. In other 105 words it lends itself to a tight packing of the ice with little loss of car space while spacing the rows of cakes and cushioning them. Any device that would allow the cakes to move materially and gain momentum thereby 110 would be objectionable, and tight packing of the ice is highly desirable.

I contemplate as being included in the present invention all such changes, departures and modifications from what is thus 115 illustrated and described as fall within the scope of the appended claims.

I claim:

1. An ice protector of the character described comprising a network of cushioning material adapted to lie upon the exposed vertical surface of a row of cakes of ice, with supporting means for holding said network suspended to lie upon such surface in operative position. 120

2. The combination of claim 1 hereof in which shock absorbing elements of said network are of rope. 125

3. The combination of claim 1 hereof in which said supporting means comprise a plu- 130

rality of devices each of which is adapted to rest upon the upper surface of the row of ice cakes.

4. The combination of claim 1 hereof in which said supporting means are adapted to rest upon the upper surfaces of ice cakes in the row and said network consists of substantially vertically-hanging cord-like members and the cushioning material comprises rope-like members extending transversely and carried by said vertically extending members.

5. A shock absorbing device for ice in transit comprising a supporting member adapted to rest upon the upper surface of an ice cake, and shock absorbing means pendent from said supporting member.

6. A packing device of the character described comprising a flexible network including flexible vertical members and flexible vertical transverse members, some of said members being of cushioning material, with means for supporting said network suspended.

7. The combination of cakes of ice packed for transit with the cakes arranged in transverse rows, there being a plurality of such rows extending longitudinally, adjacent ones of the rows being close together, with shock absorbing devices between some of the adjacent rows, each of said shock absorbing devices comprising a flexible network extending between adjacent rows, with means for supporting the network in operative position.

8. A shock-absorbing device for ice in transit comprising a plurality of hook-like members adapted to rest upon the upper surface of a tier of ice cakes adjacent to an edge thereof, and soft and flexible cushioning material suspended from said members.

40 9. A shock-absorbing device for ice in transit comprising a plurality of shock absorbing elements of rope, and a plurality of hook-like members adapted to rest upon the upper surface of a row of ice cakes adjacent to an edge thereof and supporting said shock absorbing elements.

OTTO STRUFE.
